attorney.

United States Patent Office.

D. C. GUTTRIDGE, OF PITTSBURG, PENNSYLVANIA, ASSIGNOR TO HIMSELF
AND R. A. DUNN, OF SAME PLACE.

Letters Patent No. 99,431, dated February 1, 1870.

IMPROVED LEATHER-SAMMIER.

The Schedule referred to in these Letters Patent and making part of the same.

To all whom it may concern:

Be it known that I, D. C. GUTTRIDGE, of Pittsburg, in the county of Allegheny, and in the State of Pennsylvania, have invented certain new and useful Improvements in Leather-Sammiers; and do hereby declare that the following is a full, clear, and exact description thereof, reference being had to the accompanying drawings, and to the letters of reference marked thereon, making a part of this specification.

The nature of my invention consists in the construction of a leather-sammier for pressing the water from the skins, as will hereafter be fully set forth and described.

Figure 1 is a side elevation of my invention.

Figure 2 is an end view of the frame, showing the wheels upon the ends of the rollers.

Figure 3 is a vertical section view of the rollers.

Figure 4 is a horizontal section of the same.

Letter A represents the legs or standards, which serve as a support to the rollers B. These legs are made to branch out at their bottom, so as to form a firm base, strengthened by the braces D, and have a vertical slot cut in their top, which serves as a bed to the slides attached to the ends of the rollers.

These rollers consist of round iron or wooden bars, over which there is placed a coating of rubber, so as to form a soft, yielding surface. Upon the ends of each of these there is placed a cog-wheel, C, which gear together, and receive their motion from the small wheels E, attached to each one of the handles.

In order to regulate the pressure of the rollers on

the leather, there has been a movable slide, G, secured to each one of the rollers, moving up and down in the slot, formed in the top of the standards A, and regulated by the thumb-screws H, which have their bearings in the cap-pieces K.

Placed just under the lower roller there is a long strip of rubber, or any suitable material, which acts as a scraper, L, to clean the roller of all water, &c., that may cling to it. This strip is firmly secured between the two metal plates M, the ends of which are secured in the bottom of the slot in the standards, either by wedges or any suitable device. As there is an opening formed in the under side of these plates, which passes over the sides of the standard, it also serves as a brace to steady the upper part.

Having thus described my invention,

What I claim, and desire to secure by Letters Patent, is—

1. The combination, in a leather-sammier, of the rollers B B, and the scraper L, in the cross-bar M, under said rollers, all substantially as specified.

2. In combination with the rollers B B, the movable slides G G, controlled by the thumb-screws H H through the cap-pieces K K, substantially as specified.

In testimony that I claim the foregoing, I have hereunto set my hand, this 19th day of May, 1869.

D. C. GUTTRIDGE.
